JAY J. JAKOWSKY, OF LOS ANGELES, CALIFORNIA.

PROCESS AND APPARATUS FOR TREATING BITUMINIFEROUS MATERIALS.

Application filed May 16, 1922. Serial No. 561,386.

This invention relates to a process and apparatus for treating organic substances and especially organic substances containing bituminiferous or resinous materials, 5 for the extraction therefrom of hydrocarbon or resinous products, including oils and gases or for the production of useful residues.

Although the invention has a wide field 10 of applicability and usefulness, it is particularly applicable and useful in distilling bituminiferous materials for the production of commercially valuable hydrocarbon oils and gases therefrom, and, when certain 15 materials are treated, for the production also of useful residues. Examples of bituminiferous materials which may advantageously be treated by the process and apparatus constituting my invention are 20 shales, coal, peat, wood and lignite. These materials, upon the destructive distillation contemplated by my invention, can be made to yield distillates, such as oily and gaseous hydrocarbons or resinous material, of considerable commercial value, and, more particularly in the case of coal, a valuable residue in the form of a particular high grade 25 of coke.

The materials selected for treatment may 30 vary widely and will depend upon the distillates or residues desired.

A general object of the invention is to enable large quantities of the selected materials to be treated in any interval of time; 35 that is, during "any one run" of the apparatus, and at a minimum expense as to time consumed, heat employed, and care and attention required.

In the attainment of the general object 40 referred to, certain difficulties encountered and disadvantages inherent in the practice of prior processes and in the operation of prior apparatus have been overcome by the novel process and apparatus constituting 45 my invention.

A common practice in the art has been to heat the material undergoing treatment in a retort to the distillation temperature by conduction; that is, by initial application 50 of the heat by contact of a heating medium directly with outer particles of the mass of the material and by heat transference thereafter from particle to particle inwardly throughout the mass. This has been found 55 to be an efficient and economical manner of heating, but certain difficulties have arisen

therefrom in the distillation process, the chief of which relates to the creation in certain portions of the mass of material treated of temperatures not only higher than those required for the extraction of the volatile hydrocarbons but so high as to decompose those hydrocarbons into lighter and less commercially valuable products. This objectionable result occurred particularly in 60 the distillation of such bituminiferous materials as shales and coal. Due to the comparatively low thermal conductivity of these materials, the outside portions of the mass undergoing distillation, which were either in 65 contact with or in close proximity to the source of heat, rapidly rose to a higher temperature than that of the interior particles of the mass. As a result of this non-uniform heating, the distillation process was 70 very much more rapid in the outside or more highly heated portions of the material; and after the hydrocarbon vapors had been formed and driven therefrom, these outside 75 portions of the mass still presented zones of heat through which the distillation vapors evolving from the interior were compelled to pass. These zones of heat were generally of so high a degree that the vapors resulting from the interior distillation 80 in passing therethrough were decomposed to the lighter and less commercially valuable hydrocarbons, and also in large degree, to non-condensable gases of little commercial value. The character of the distillation 85 process was therefore not uniform throughout the mass of material treated. This difficulty was encountered particularly where an attempt was made to treat a large body 90 of the material in retorts and by a comparatively high degree of heat in order to hasten 95 the time of the process.

One of the particular objects of my invention, both as to the process and as to the apparatus, is to overcome the difficulties 100 referred to above. To that end, by the novel process, and, if desired, by use of the novel apparatus, the mass of the material treated is kept moving in a direction to advance successive portions and particles 105 thereof through the region of the immediate heating zone; that is, through the region of the comparatively rapid and initial application of the heat. The mass is also subjected to a current of a suitable fluid 110 medium to drive off from the particles and portions of the mass thus advanced through

the heating zone the resulting oils, vapors and gases of distillation, to evenly distribute the acquired heat throughout the mass, and to reduce the temperature of any portions 5 which have risen high enough to deleteriously affect distillation products evolving from the other portions. Preferably, the entire mass of the material is given such movements in successive cycles as to ultimately 10 advance substantially all portions and particles thereof a number of times through the heating zone referred to, the result being an extremely thorough and complete extraction from each particle of 15 its distillable hydrocarbon content. Desirably also, the current of the fluid medium is sent through the mass of material in a direction driving the distillation products rapidly away from the initial heating zone to 20 ward the vapor eduction conduit of the apparatus, so that the vapor, once formed by the distillation of the material, cannot again come into the initial heating zone, and the danger of increments of heat in the distillate 25 extending to its decomposition is avoided.

It has been discovered by extensive experimentation that the maximum yield of oil of high grade is obtained by causing the oil-bearing material to gradually reach 30 the temperature of complete distillation. The gradual heating of large masses of the material up to the temperature of complete and uniform distillation of all its portions is, however, attended with difficulties where the 35 thermal conductivity of the material is alone depended upon for conveying the heat from the outer portions, to which the heat was initially applied, to the interior particles. Even in such gradual heating of large 40 masses, there is an inherent tendency to build up regions of greater heat in outer portions and of such intensity as to deleteriously affect the vapors of distillation finally evolving from the interior. In other words, 45 from like materials throughout the mass, uniform products of distillation are not obtained.

Another particular object of my invention is to overcome the difficulties last mentioned. To that end, in the novel process and by the novel apparatus, the mass of the materials is given the movements in successive cycles already referred to and these movements are so directed as to advance the cycles 50 progressively through an extended heating zone progressively increasing in temperature. By this treatment, the gradual increase of heat up to that of complete distillation takes place substantially uniformly throughout 55 the mass and without the creation of regions of greater heat in portions of the mass positioned to deleteriously affect the distillation products evolved from other portions.

In one form of my novel apparatus, found 60 particularly satisfactory in practice, and

later referred to as the preferred embodiment, an elongated heating chamber, situated in the retort in which the oil-bearing material is treated, is employed, and in which heating chamber a temperature is 70 maintained gradually increasing from the material-inlet to the discharge end of the retort, this heating chamber having a heat transmission wall or plate in contact with an outer layer of the material. Heretofore 75 the use of such heat transmitting means has been subject to the disadvantages of heating the material to a temperature higher than that most favorable to distillation due to direct and more or less prolonged contact of 80 the material with the heating surface. Another particular object of my invention is to improve the heat-conditions of distillation in this respect. To that end, such movements are imparted to the material undergoing treatment as to advance its particles at a comparatively rapid rate across the heating surface. Preferably, also, the current of 85 the fluid medium heretofore referred to is directed not only through the body of the 90 material in the manner and for the purpose already mentioned but through that layer of the material contiguous to the heat transmitting plate and along the surface of that plate. The current of the fluid medium thus 95 directed has a sufficiently modifying effect upon the transmission of the heat from the plate to the moving adjacent layers of the material to entirely overcome the disadvantages referred to but without reducing the 100 degree of heat transmitted below the effective range.

The current of the fluid medium directed, as stated, across the surface of the heat transmitting plate and through the adjacent 105 particles of the material being treated accomplishes also the additional purpose of sweeping the vapors of distillation, initially formed in the heating zone, past the hot surface of the heat transmitting plate so as to 110 prevent their stagnation and decomposition into less desirable hydrocarbons.

My invention also contemplates the treatment of certain heavy fractions or cuts from the distillates obtained from the process or of heavy oils obtained elsewhere, which it may be desirable to further destructively distil or to "crack" into lighter hydrocarbons, such as gasolene or other light motor-fuel hydrocarbons. To this end, the heavier 115 oils referred to may be introduced either before the distillation process hereinbefore referred to has been completed throughout the charge then being treated or after the completion of that distillation. Such treatment 120 of the heavier oils has been found particularly effective when the main charge undergoing treatment is a bituminous coal, the additional treatment of the heavier oils also resulting in an extremely high grade of 125 130

coke as a residue from the treatment of both materials.

My novel apparatus is not only applicable for the carrying out of my novel process in the treatment of the various materials referred to but has a wide variety of other uses, including the drying and calcining of materials, such as gypsum, for example.

The objects and principles of my invention, stated above, and other objects and principles, will appear from a detailed description hereinafter to be given of an illustrative embodiment of the novel apparatus in a preferred form, and of an illustrative example of the novel process. It is to be understood, however, that the embodiment and example hereinafter described are merely illustrative of my invention and that the broad scope of the invention includes various other specific constructions and processes in accordance with its principles and as defined in the appended claims.

While, as stated, my novel process and apparatus are not limited to any of the particular uses here set forth, they are particularly effective in the treatment of bituminous coal, not only for the extraction of the volatile hydrocarbons therefrom but in the production of a high grade of coke as a residue, and the latter particularly when additional treatment is given to heavier oils obtained either from the distillates of the process or from other sources. As the employment of these materials also clearly illustrates the fundamental character of the process and the principles of operation of the apparatus, in the illustrative embodiment and examples, for the sake of brevity, reference will be made primarily to the treatment of such materials.

The accompanying drawings illustrate an apparatus built in accordance with the provisions of my invention, and show a preferred embodiment thereof. In the drawings:

Figure 1 is a side elevation of the entire apparatus, and showing the elongated retort and its manner of mounting;

Figure 2 is an enlarged perpendicular transverse sectional view through the apparatus along the lines 2—2 of Fig. 1 looking in the direction of the arrow;

Figure 3 is a perpendicular longitudinal section of the apparatus along the line 3—3 of Fig. 2 looking in the direction of the arrow, and upon a scale reduced from that of Fig. 2;

Figure 4 is a horizontal section in plan of the receiving end of the apparatus along the line 4—4 of Fig. 3 looking in the direction of the arrow, and on an enlarged scale;

Fig. 5 is a perspective view of a portion of the material-receiving hopper and feed chute;

Fig. 6 is an enlarged detail view in end

elevation of a portion of the combustion flue or heating conduit, the retort, and a vapor sealing device associated therewith;

Fig. 7 is a side elevation of the sealing device and associated parts shown in Fig. 6;

Fig. 8 is a central perpendicular longitudinal section on an enlarged scale through an end portion of the retort and adjacent supporting wall and showing the details of sealing rings;

Fig. 9 is a diagrammatic plan view of the lower portion of the retort and showing the relative positions of certain pipes for the introduction of heavy oils for distillation into lighter products, and showing an inlet pipe for the fluid medium hereinbefore referred to;

Figs. 10 and 11 are diagrammatic illustrations showing the directions of movements of the material during the course of its treatment in the apparatus.

In the illustrative apparatus, an elongated retort 1, desirably from 50 to 70 feet in length and from 6 to 10 feet in diameter, is provided, the same being in the form of a cylinder or drum, preferably insulated against appreciable loss of heat by a jacket of any suitable heat insulating material.

The retort 1 is provided with riding rings 3, sufficient in numbers and suitably spaced to rotatably support the retort through the medium of pairs of rollers 4, the rollers of each pair upon opposite sides of the retort, journaled in heavy supporting brackets 5 mounted upon a suitable foundation as indicated in Fig. 1.

In the illustrative apparatus, the agitation of the material undergoing treatment in the retort, and the movements of the same in carrying out my novel process are accomplished by a rotation of the retort. To this end, a gear 6 is mounted upon the exterior surface of the retort, which gear meshes with a pinion 7 on a shaft 8, journaled in suitable bearings 9. The shaft 8 is provided with a gear 10 meshing with a gear 11 on a shaft 12 operated by rotation impelling means, here indicated as a motor 13. The speed of rotation of the retort is preferably low, for example, a third of a revolution per minute, although the speed of rotation may vary with the materials to be treated, and a speed changing mechanism of any suitable type may be employed.

The retort is mounted on its bearings in a position inclined downwardly from the receiving to the discharge end, as shown in Fig. 1, and extends at these opposite ends through the walls 14 and 15 of brickwork or other suitable foundation material. The walls 14 form a casing at the receiving end of the apparatus and the walls 15 a casing at the discharge end. Within the casing 14 is contained the mechanism for feeding the charge into the retort, and in the casing 15

the heat generating means and discharging devices for the residue from the process of distillation.

As shown in Fig. 3, the retort extends freely at its opposite ends through the walls 14 and 15, so that the entire mounting of the retort is such as to permit longitudinal movement thereof due to expansion, the riding rings 3 and the gear 6 partaking of sliding movements on the rollers 4 and the pinion 7 respectively, in any such longitudinal movement. It is, of course to be understood that any suitable form of thrust bearings are to be employed to prevent the retort from working toward the lower end. In actual practice thrust bearings are mounted either on the stationary supporting brackets 5 or on additional brackets provided for that purpose to engage either one of the middle pair of riding rings 3. As such constructions are well known and constitute general engineering practice, it has not been deemed essential to illustrate them here, and also as their omission simplifies the side elevational showing of the entire apparatus presented by Fig. 1.

This free mounting of the ends of the retort through the walls 14 and 15 requires some form of a gas-tight joint. One desirable form of such a joint is shown in Fig. 8, and comprises two telescoping rings, one rigidly mounted on the immovable wall through which the retort extends and the other mounted on and rotating with the retort, and a packing between them. Each ring has a flange for its mounting and free annular portions in telescoping relation. The ring mounted on the retort is indicated by the numeral 16 and the ring mounted on the wall is indicated by the numeral 17. The closure and packing between the telescoping rings is formed by the ring-disk 18 and parts carried thereby. This ring-disk 18 is freely mounted surrounding the retort 1 and with one of its side faces bearing against the free annular edge of the ring 16; with which it is held in contact by springs 19; the tension of which may be adjusted by screws 20. Each spring 19, as shown, abuts against the flange of the ring 17 which mounts that ring upon the wall 15; and the adjusting screws 20 pass through the ring-disk 18. A sufficient number of springs 19 is employed to properly center the ring-disk 18 in its sliding contact with the ring 16; and to prevent rotation of the ring-disk 18 guide pins 21 are employed. These pins are affixed in the flange of the ring 17 fastened to the wall 15, and extend therefrom loosely through holes in the ring-disk 18. The ring-disk 18 bears an annular gland 22 with suitable packing 23 therein, bearing upon the outer cylindrical surface of the ring 17, the whole forming a gas-tight joint between

the telescoping portions of the rings 16 and 17. The arrangement of parts described produces a particularly effective joint since the only parts in sliding contact are the free annular edge of the ring 16 and the flat surface of the ring-disk 18. Such an arrangement also provides for a close sliding contact between the parts notwithstanding eccentric movements of the ring 16 due to warping of the retort out of true cylindrical form. A riding ring 3 for the retort is placed closely adjacent each of the rings 16 to minimize eccentricity due to warping of the retort, one such riding ring 3 being shown in the location referred to in Fig. 1.

Any suitable form of furnace may be used as a source of heat, and the details of the particular furnace employed in the illustrative apparatus will later be referred to. The combustion chamber of the furnace is indicated generally by the numeral 24 in Fig. 3. As shown, the rotating retort 1 extends through the forward wall 15 of the casing containing the discharge conduit, the furnace and its combustion chamber, but terminates short of these portions of the apparatus. A combustion flue 25 forming a heating conduit extends longitudinally through the retort parallel with the axis of rotation thereof and, as shown in Fig. 3, toward the furnace end of the apparatus beyond the end walls of the retort in a position superimposed upon the upper wall of the combustion chamber. An opening 26 in the bottom of the heating conduit permits the flow of the heating medium from the combustion chamber directly upward into the heating conduit and thence along to the exhaust flue of that conduit. The heating conduit terminates, as shown at the right hand side of the apparatus as viewed in Fig. 3, closely adjacent the material-receiving end of the retort, which projects through the wall of the casing 14. The conduit is supported, as will later be shown in detail, so as to permit free rotation of the retort thereabout. A pipe 27 discharges the exhaust gases from the heating conduit through the casing 14 and ultimately upward through the stack 28 to the atmosphere.

The chief fuel used in the retort is preferably the non-condensable gases produced during the distillation process. These gases constitute the "reject" from the condensing plant and are stored in ordinary gas holders until required. If, for any reason, such gases are not available when the retort is being started up, crude oil is used in the burner 29, provided for the purpose. In a short time after operation begins, sufficient non-condensable gases are being produced and when that point is reached the supply of crude oil is shut off, and the gas is intro-

duced through the burner 30. Valves 31 and 32 are employed to control the quantity of fuel and hence the degree of heat employed. The air for supporting the combustion in the furnace may enter through a damper 33 or through an additional air port 34, or through both.

The furnace is controllably operated to maintain a heating zone in the retort, later to be referred to in detail, of intensities of heat depending upon the materials to be treated and gradually increasing from a minimum at the receiving end of the retort to a maximum at the discharge end.

As shown more particularly in Fig. 2, the heating conduit is disposed longitudinally of the retort, parallel with its axis of rotation and to one side of the axial center. The heating conduit is desirably formed with interior walls of fire-brick or other suitable refractory material built in a suitable steel framework, but with the wall facing the axial center of the retort formed of a more ready heat-conducting material. In the illustrative apparatus, a metallic heat conducting and heat-transmitting plate 35 is employed for the wall referred to. This plate may be formed of calorized iron, copper, or brass, or any composition adapted to resist high temperatures and at the same time readily conduct and radiate the heat. The plate is provided with suitable ribs or projections 36 to increase its structural strength and radiation efficiency. These ribs are spaced apart along the length of the plate and extend vertically and hence at an angle to the longitudinal axis of the heating conduit and to the axis of rotation of the retort. As will later more fully appear, these ribs, thus positioned, aid in the movement of the material undergoing treatment from the receiving to the discharge end of the retort during the rotational movements of the retort about the heating conduit.

The location of the heating conduit to one side of the axial center of the retort, as shown in Fig. 2 and with the heat-transmitting plate occupying a vertical position, enables the feeding of a large body of the material into the retort and its subsequent treatment therein. As viewed in Fig. 2, the rotation of the retort is in a clockwise direction. As a result of such rotation, the bed of material fed into the retort is given a turning movement against the heat-transmitting plate as an abutment, which movement piles up the material between that plate and the opposite wall of the retort, the upper surface of this material advancing to a position inclined from the wall of the retort downwardly to the plate. A continuation of the rotation of the retort advances the turning movement of the body of the material and the inclination of its upper layer beyond the angle of repose of its particles and

a "tumbling" of the material occurs downwardly toward and into contact with the heating plate. This "tumbling" movement brings fresh particles from the body of the mass to the surface to in turn partake of the "tumbling" movement as the mass continues to advance beyond the angle of repose of these particles. The inclination of the upper surface of the body of the material causing the "tumbling" movements referred to, is indicated by the letter T in Fig. 2. Partly by gravity and partly by reason of the continuous turning movements imparted to the body of the material, the particles thus advanced into contact with or into heat-receiving relation with the heat-transmitting plate, continue downwardly toward the bottom of the retort and then upwardly again in cycles of movements, the importance of which movements in the distillation process will later be referred to in greater detail. The ribs or projections 36 upon the heat transmitting plate, extending vertically, and hence at an angle to the axis of rotation of the retort, with the inclination toward the discharging end, function by reason of the rotation of the retort, in advancing the material in these cycles of movements toward the discharge end.

The arrangement of the heating conduit with the heat-transmitting plate closely adjacent the axial center of the retort is also of some importance in relieving the heat transmission plate of the excessive strains thereagainst, which would otherwise be caused by pressure of the material being treated. The material, considered as a body, by reason of the rotation of the retort partakes of a slight pivotal movement about the axis of rotation of the retort and this pivotal movement tends to lessen the pressure of the body of the material below that axis against that plate.

This pivotal movement is found to occur to a more marked degree when the particles of the material stick or coalesce into a compact body throughout the mass of the material being treated. In the distillation of certain bituminiferous materials, there is a tendency of the particles of the material to thus stick together into a compact body due to the oily contents distilled therefrom and present on their surfaces, and the formation of such a compact body seriously interferes with the progress of the distillation process. In the present arrangement of the parts of the apparatus, however, any substantial continuation of the pivotal movement of such a mass would cause the mass to rise from the supporting bottom of the retort to an unstable position, from which a gravity fall would occur causing a breaking up of the mass into its original constituent particles.

The means adopted in the illustrative apparatus for feeding the charge of the ma-

terial to be treated into the retort is shown in Figures 1, 3, 4 and 5.

The material to be treated is placed in a hopper 37 through which it is fed downwardly by gravity into a material-receiving chamber 38, which is surrounded by the pre-heating chamber 39. This hopper 38 is of sufficient height and width to accommodate a substantial supply of the material. The pre-heating chamber 39, communicates at its lower portion with a flue 40. The flue 40 in turn communicates at one side with the flue 27 delivering the exhaust gases from the heating conduit and at the other through a by-pass flue 41 with the stack 28, the by-pass flue being controlled by a damper 42 controlled by a damper rod 43. The upper portion of the heating chamber 39 communicates with the stack 28 through a flue 44. It is obvious from the structure shown and described, that the hot gases from the heating conduit may be discharged directly into the stack 28 without entering the heating chamber 39, when the damper 42 is moved to the position opening the by-pass 41 and closing the communication between the flue 40 and the chamber 39, or such gases may be circulated only through the heating chamber 39 and upwardly through the exit flue 44 to the stack by closing the damper 42. It is also apparent that by setting the damper 42 to intermediate positions, the degree of heat imparted to the material in the chamber 38 may be controlled as desired.

The material-receiving chamber 38 terminates below in an inclined feed trough 45 having a curved bottom of relatively large dimensions in which is located a feed screw 46. The feed screw is slowly revolved by the worm gear 47, which may be driven through suitable gearing connected with the mechanism driving the retort, or, preferably, by an auxiliary variable-speed electric motor. That portion of the shaft of the feed screw 45 extending through the heating chamber 39 is desirably protected by a bushing 48. By placing the feed screw 46 in the bottom of such a feeding trough as is here shown, it is possible to feed in much coarser material than could be efficiently handled by a closed-tube worm feed, thus avoiding the necessity of crushing the material to as fine a mesh as would be necessary if a feeding device of the latter type were employed.

Because of the location of the heating conduit to one side of the axial center of the retort, the charge feeding means is placed on the opposite side of that axial center, as clearly shown in Fig. 4. The material is continuously fed into the retort and piles up between the heat transmitting plate and the opposite wall of the retort in the manner hereinbefore stated.

A conduit for the removal of the vapors of distillation is disposed on one side of

the body of the material in the retort and a supply line for fluid under pressure with nozzles for directing a current of the fluid medium through the body of the material and toward the vapor-eduction conduit 70 disposed on the other side. In the illustrative apparatus, the vapor eduction conduit is disposed above the body of the material in the retort and the fluid supply line below, although these particular positions 75 are merely illustrative and are not essential to my invention.

The vapor conduit, shown in cross section in Fig. 2, and indicated by the numeral 49, is virtually a large box girder of sufficient strength to meet the strains imposed upon it, and comprising inner and outer walls. The inner walls form a central chamber for the reception and ultimate withdrawal from the apparatus of the vapors 85 of distillation and any condensation fractions occurring therefrom as the vapor traverses the conduit. The outer walls form a cooling jacket about the interior chamber, through which jacket water is circulated 90 as a cooling medium.

The vapor eduction conduit is supported rigidly in the wall 15 at the discharge end of the apparatus, as shown in Fig. 3, and extends through the receiving end of the 95 retort into the casing 14 where it is slidably supported upon rollers 50 mounted upon a suitable base 51, to provide for expansion of the structure of the conduit.

In the illustrative apparatus, the heating 100 conduit is supported by suitable beams from the vapor-eduction conduit. The ribs or projections 36, heretofore referred to as extending from the heat transmitting plate of the heating conduit, may be used for such supports, and are shown in the illustrative apparatus attached at their upper ends to the structure of the vapor eduction conduit. Other beams 36' of like construction are shown upon the rear side of the two conduits, as shown in Fig. 2.

As the heating conduit is suspended from the vapor-eduction conduit, to provide for longitudinal expansion of the heating conduit the exit flue 27 extends through a bushing 52 mounted upon the flue 40 of the pre-heating chamber 39. The flue and the bushing present a sliding fit and, to provide a gas-tight joint between them, a gland 53 containing suitable packing 54 is employed. The space between the upper wall of the heating conduit and the bottom wall of the water jacket of the vapor-eduction conduit is preferably filled with any suitable heat insulating material, as indicated at 25' in 115 Fig. 2.

The chamber of the vapor-eduction conduit communicates with the retort through tubes 55, one of which is shown in Fig. 2. These tubes are spaced apart longitudinally 130

of the conduit and hence of the retort, and each is controlled by an inlet valve 56 of any suitable type operated from without the retort. In the illustrative apparatus, the 5 valves 56 are indicated as pivotally mounted to swing in their own planes and operated by rods 57 suitably journaled for longitudinal movement through the retort and extending through a wall of the casing 14 as 10 shown in Figs. 3 and 4 to positions for their manual operation. These inlet tubes and valves for the vapor eduction conduit are desirably spaced about 5 feet apart although this detail of spacing is not an essential feature of my invention. Separate means for 15 operating the valves are employed, as indicated, for the purpose of controlling the hydrocarbon recovery. One example of such control is as follows: If it is desired to 20 withdraw only the lighter hydrocarbons or more volatile fractions and keep the heavier hydrocarbons within the retort for redistillation and cracking, the valves in the hotter regions of the retort, toward the delivery 25 end, would all be closed and only a few valves in the cooler part, near the inlet end, would be opened. The open valves would create a current of the vapors coming from the material undergoing treatment toward the inlet 30 or cooler end of the retort, and hence counter-current to the cooler throughgoing material. The heavier hydrocarbons in this vaporous current, with boiling points below that temperature existing where the valves 35 are open, would condense on the surface of the throughgoing material, while the lighter hydrocarbons with boiling points above that temperature would still remain in the vapor state and be drawn off through the vapor 40 line. The heavier hydrocarbons thus condensed upon the surface of the throughgoing material would then be carried back into the hotter regions of the retort where redistillation and cracking would take place. 45 Within the chamber of the vapor-eduction conduit and immediately below the inlet tubes 55 is positioned a shield or baffle 57', extending longitudinally of the chamber. Any suitable suction means is employed, com- 50 municating with the vapor-eduction chamber, to accelerate the withdrawal of the vapors of distillation from the retort and their passage through the chamber. As these vapors enter and travel along the eduction chamber any beads or fine liquid particles of oil carried thereby or condensed therefrom during their travel drop by gravity upon the shield or baffle 57', flow downwardly thereacross and drop therefrom to that 55 portion of the chamber therebelow. Condensation occurs to a considerable extent in the vapor-eduction conduit and the condensed oil finds its way to the bottom of that conduit, and as it is inclined at the inclina- 60 tion of the retort, the condensed oils flow 65

toward the discharge end of the apparatus. The shield 57' also functions to prevent the hot incoming vapors from coming into direct contact with the stream of condensed oil flowing along the bottom of the conduit. 70

At the lower end of the vapor-eduction conduit, the condensed oil is removed through the drain pipe 58, while the uncondensed vapors and gases pass out under suction through the main vapor line 59 to 75 the condensing and recovery plant.

A pipe for the supply of the fluid medium to be forced in a current through the material in the retort, is positioned longitudinally of the retort and immediately below 80 the heating conduit. Any fluid medium can be used which does not deleteriously affect the process of distillation, and the fluid used will, to some extent, depend upon the materials to be treated. In the present illustrative example of the use of the apparatus, the fluid medium employed is that of steam. The steam for this purpose is generated in a boiler 60, preferably disposed in the combustion chamber 24, and from which leads a 85 steam pipe 61, having nozzles 62, preferably spaced about one foot apart longitudinally of the retort.

As shown particularly in Fig. 2, the fluid supply pipe is positioned in the longitudinally extending pocket formed by the inclined surface of the material projecting below the heating conduit, the bottom of that conduit and the adjacent wall of the retort. 90 The nozzles are positioned to direct the current of the fluid medium immediately against the depending portions of the body of the material; and therefrom fluid streams spread upwardly through the body of the material and across the heat transmitting plate. The 95 voids formed between the irregular particles of the material and the heat transmitting plate with which they are in contact readily permit this flow of the fluid medium upwardly and substantially across the heat-transmitting plate. 100

The streams of the fluid medium referred to may accomplish various functions depending upon the uses to which the apparatus is put in the treatment of various materials. 105 These will later be referred to in giving an illustrative example of my novel process.

My invention also contemplates the treatment of comparatively heavy oils to obtain therefrom lighter hydrocarbon oils, such as particularly as the various motor-fuel oils. The novel apparatus, therefore, also contemplates the employment of oil lines, indicated by the numerals 63, 64 and 65, Fig. 2, 110 for the purpose of introducing certain fractions or cuts from the distillate obtained in the process or oils obtained elsewhere, and which it may be desirable to crack into gasoline or other light hydrocarbons for motor 115 use. 120

As no two oils yield the maximum of motor fuel by the same temperature treatment, it is essential, where provision is to be made for the treatment of different oils, to introduce these oils into different temperature-zones of the retort. Mixtures of the paraffin and the aromatic series of derivatives, such as those obtained from bituminous coal treated in the apparatus, require, for example, a temperature higher than that required for decomposing oils of the paraffin-base hydrocarbons, such as are found in the natural petroleums. The first mentioned oils give a maximum yield of motor fuel hydrocarbons at about 600° C. and the other at about 550° C. To provide therefore for the treatment of various oils, the oil lines in the present apparatus extend from the receiving end of the retort longitudinally thereof to discharging positions at different points in the retort. This is diagrammatically shown in Figure 9. As also shown in Figure 9, a single manifold 66 may desirably be used with branches thereof comprising the oil lines referred to extending into the retort and each having valves 67 for controlling the supply therethrough.

Reverting again to the furnace and material-discharging means of the apparatus, as already stated, any form of furnace may be used as also any suitable means for discharging the spent materials or residue from the retort.

In the treatment of some materials, a discharge chute extending into a column of water may desirably be employed, particularly where the residue of the material treated contains water-soluble residues of sufficient commercial value to warrant the expense of their recovery. Some shales, for example, contain potassium or other water-soluble compounds which are leached out when the highly heated shale-residue enters the water, and which can be recovered from the resulting liquor. The advisability of such a discharge of the residue for recovery of the water-soluble contents can be determined by analysis made of samples taken from time to time. Many varieties of shale, however, as well as a large number of other materials do not contain water-soluble residues of sufficient commercial value to justify their recovery. In the illustrative apparatus, a form of regenerative chain-grate discharge useful in the treatment of a wide variety of materials, and particularly in the treatment of coal is preferably employed. As heretofore stated, a particularly high grade of coke can be produced in the particular apparatus selected as an illustrative embodiment of my novel apparatus; and, as the rapid quenching of coke in water produces a more friable product and also usually makes a drying operation necessary, I pref-

erably employ the regenerative chain-grate discharge hereinafter to be described in detail. It is to be understood, however, that my invention also contemplates the employment of a water-seal discharge of the residue, where that is desirable.

Taking coal as the material undergoing treatment in the illustrative example, the coal by the time it reaches the lower end of the retort, has been reduced to the form of coke by the distillation therefrom of from 80 to 95% of its volatile hydrocarbon content. The coke discharges from the retort into the vertical column 68, which is preferably from 5 to 8 feet in height and rectangular or oval in cross section, and desirably of dimensions approximately 1½ feet by 3 feet for the particular apparatus illustrated.

A traveling chain grate of any suitable type, and indicated generally by the numeral 69 is disposed below the combustion chamber, and extends at the discharge end of its travel through the air inlet port 34 and at the receiving end of its travel transversely across the lower portion of the discharge chute 68 in position to receive by gravity thereon the coke descending through the chute from the retort. A continuous discharge of the coke takes place due to the slow travel of the grate. The temperature of the coke in the descending column 68 is slightly lower than that at which it was discharged from the retort (600 to 900° C.). The coke is conveyed outwardly through the air inlet port 34 and discharged upon a conveyor 70 by which it is conveyed to any place desired.

By the arrangement of the chain grate below the combustion chamber, gradual cooling of the coke is obtained with the recovery of its heat by preheating the air for combustion. The air for supporting combustion in the furnace enters above the discharging coke through the port 34 and travels counter-current to the outgoing coke.

To avoid combustion of the coke in the regions of its travel on the chain grate where its heat is still great enough to cause combination of the oxygen of the air therewith, and yet to impart as much of this greater heat as possible to the incoming air, a heat-receiving and heat-radiating partition, indicated by the numeral 71, is extended from the wall of the column 68 rearwardly immediately over the chain grate and hence over the regions of greatest heat of the coke upon that grate. The partition is made of any suitable heat-conducting material which will receive heat from the immediately underlying layer of coke by radiation and rapidly transmit that heat to the column of air advancing above the partition. Desirably, the partition is made of sheet iron. By this arrangement, the air after traveling for some dis-

tance inwardly of the air port 34 in direct contact with the less highly heated particles of the coke, passes above the sheet iron partition referred to where it becomes further 5 preheated from the outgoing coke, and yet without such contact therewith as to cause its combustion. The air after traversing the upper surface of the partition 71 passes into the combustion chamber through a port 10 72 controlled by a damper 73 operated by a damper rod 74 from outside the furnace. The air entering the furnace supplies the oxygen for the combustion of the fuel delivered through the burners 29 or 30, and 15 the hot gases of combustion pass upwardly through the port 26 into the heating conduit; as hereinbefore stated.

A gate valve 75 adjusts the feed from the discharge chute 68 upon the chain grate. 20 The speed of the traveling grate and the feed of the coke thereon are desirably adjusted so that the temperature of the coke when it emerges from under the partition 71 will not be greater than approximately 200° C. The 25 incoming air, therefore, is heated first by direct contact of the coke to about 200° C., and as it passes up and travels along the sheet iron partition, the additional heat will be absorbed. The partition is placed as 30 close as possible to the traveling coke bed, and because of the thinness of the layer of the coke on the chain grate and its slowness of travel, the efficiency of the heat recovery is fairly high. Any residual inflammable 35 gas in the coke will be picked up by the air and carried into the furnace for combustion.

Near the upper part of the column of coke in the chute 68 is a steam line 76 for admitting steam or superheated steam for 40 the recovery of nitrogenous compounds, if desired. Such gases, generated by the steam, would be carried up into the retort and thence out by the vapor line into the recovery system.

45 Baffles 77 and 78, of ordinary construction, are disposed above the chain grate, so that the incoming air, after passing the first baffle 77 comes into contact with the lower side of the baffle 78, which is in the 50 region of greatest heat in the combustion chamber and thereby additional preheating of the air for combustion is effected.

From a coke recovery standpoint, the furnace and its associated parts thus described 55 present several advantages: The coke is gradually cooled instead of being rapidly quenched by a water bath or spray, thus preventing disintegration of the product. The residual heat in the coke is recovered and 60 utilized for the preheating of the air supply for combustion. All of the combustible gases and vapors in the coke are driven off during the cooling of the coke and conserved for use in the furnace. And finally,

a dry coke is produced which, because of its moisture-free condition, has a greater heat value, and is also better suited for mixing with a suitable binder and briquetting. 65

For the treatment of oil-bearing shales, the same type of furnace and chain-grate discharge may be used, although the horizontal baffle walls 77 and 78 are preferably eliminated, and the spent shale burned directly upon the chain-grate, the position of the oil and gas burners being changed, if necessary, to burn the ash efficiently. The ash may then be leached if water-soluble 70 contents of sufficient commercial value are present. 75

To prevent the fine liquid particles, vapors and gases of distillation from sweeping upwardly over and to the rear of the vapor and heating conduits in the retort, and to prevent a rearwardly sweeping movement of the steam or other fluid medium issuing from the nozzles 62 (Fig. 2) to the rear of the heating conduit, devices functioning as reflectors or seals or both may desirably be employed between the walls of 80 the retort and the vapor and heating conduits. 85

With the parts as arranged in the illustrative apparatus, these devices function both as deflectors and seals and are above 90 the vapor conduit and below the heating conduit, respectively, although it is to be understood that this arrangement of the various parts are merely those selected in the 95 illustrative embodiment and to illustrate the principles of the invention. 100

The two deflecting and sealing devices in the illustrative apparatus are shown as drag plates functioning as deflectors and seals, although it is to be understood that my invention is not to be limited to the 105 particular forms of the deflectors and seals here shown. The upper device illustrated in Fig. 2, comprises a channel iron 79 extending lengthwise upon the cover of the vapor conduit, in which channel iron is freely journaled for pivotal movement an elongated rib 80 projecting from an elongated sealing plate 81, co-extensive with that portion of the vapor conduit within the retort. The deflecting and sealing plate 81, has weights 82 and 83 in the form of channel irons affixed to its under surface adjacent each side edge thereof and of such relative masses as to maintain the plate in a 110 position upwardly inclined with its outer side edge in gas-tight but sliding engagement with the interior cylindrical surfaces 115 of the retort.

The lower drag deflector and seal, illustrated in Figs. 2, 6 and 7 is designed also to provide an end seal to prevent leakage of the vapors and gases around the end of the heating conduit adjacent the receiving 120 125

end of the retort. The plate of lower drag deflector and seal, indicated by the numeral 84, is pivotally suspended from the angle iron 85 attached to the lower rear edge of 5 the heating conduit.

An elevational view of that end of the heating conduit in the receiving end of the retort, and showing an end elevational view 10 of the lower drag seal, is shown in Fig. 6. To the end of the heating conduit is attached a steel plate 86, desirably of the contour shown, and which extends forwardly of the front face of the heating conduit and is designed to be buried vertically in 15 the mass of the material within the retort. Upon the end of the drag plate 84, is attached in perpendicular position a plate 87 shown in edge view in Fig. 7, desirably of the contour shown in dotted lines in side elevational view in Fig. 6, and having its 20 lower edge of the curvature of the interior wall of the retort, as also shown in Fig. 6, and which reposes by gravity in sliding contact with that wall. The plates 86 and 25 87 and are disposed as closely adjacent as will permit the expansion of the drag plate 84. Such an arrangement, it is obvious, prevents substantial leakage of vapors past the end of the drag plate.

30 The drag sealing plates 81 and 84 are not absolutely essential to the practice of my invention although in the illustrated apparatus they are preferably used. In case the interior walls of the rotary retort are 35 built of a material rendering these drag sealing plates impracticable or difficult of use, they may be dispensed with, and the steam from the pipe 61 may be directed with such pressure as to sweep through the 40 material undergoing distillation and to the vapor eduction ports, so as to carry the products of distillation with a minimum of dissipation of the steam and the products throughout the retort.

45 In the discharge end of the vapor conduit, shown disposed above the furnace in Fig. 3, is placed a clean-out cover 88, provided with a "look-box" 89 for observing the vapors emerging from the retort. The 50 combustion flue forming the heating conduit for the retort is also provided with a similar clean-out cover 90 and "look-box" 91.

55 My novel process may be performed in the hereinbefore described apparatus, and in giving an illustrative example of its performance, reference will primarily be made to coal as the material undergoing treatment, although, as hereinbefore stated, this 60 material is merely typical of various materials which can be treated by my novel process and in my novel apparatus.

In starting the process, and before the 65 non-condensable gases constituting the "reject" from the distillation process are

available, oil from any suitable source, is delivered to the burner 29, and after the heated gases have traversed the heating flue a sufficient length of time to raise the temperature of the heat-transmitting plate to 70 the required degrees, the coal will be fed into the retort through the feeding-in means hereinbefore described.

As hereinbefore stated, the coal will be fed into the bottom of the retort to one side 75 of the heat transmitting plate, and upon a sufficient quantity being fed, the material will build up in the receiving end of the retort in a body against the heat transmitting plate. The initial position of this 80 body of the material is in the cooler portion of the graduated heating zone within the retort. Although the temperature throughout the retort will vary according to the materials under treatment in the treatment 85 of the material now under consideration, the temperature at the discharge end will be approximately 600 to 900° C., and will gradually decrease toward the intake end. Preferably, the temperature will not rise 90 above approximately 500° C. in that portion of the distillation zone in which the hydro-carbon vapors are driven off the material, although the lower portion of the retort nearer the discharge end may rise to higher 95 degrees of temperature.

The material is desirably preheated before being fed to the retort in the manner hereinbefore stated, and the temperature of the material gradually increases as it moves toward the discharge end of the retort.

During the movement of the material from the receiving to the discharge end of the retort, the heat is initially applied thereto by immediate contact of the heat-transmitting plate with those particles of the material in contact with that plate, and heat is thereafter conducted from particle to particle inwardly of the mass. The heating zone of the degrees necessary for distillation 105 need not, however, extend throughout the mass of the material. It has been found to be desirable in practice to maintain degrees of heat in the heat-transmitting plate which establish an effective heating zone extending approximately six inches outwardly from the surface of the plate. The depth 110 of this heating zone, effective for distillation, into the body of the material may vary, however, and my invention is not to be 115 understood as limited to the particular figures here given. Rotation of the retort causes agitation and tumbling of the material, producing cycles of movements causing substantially all particles of the material to traverse at intervals the heating zone effective for distillation of the volatile hydro-carbon contents.

The vertically disposed ribs on the heating plate and the rotation of the retort and 120

its angle with the horizontal cause progressive advance of the material in these cycles of movements through the heating zone referred to and in the direction of the gradually increasing degrees of temperature.

As already stated, the heat transmitting plate is placed to the right of the center line of the retort, as the parts are viewed in Fig. 2. Figs. 10 and 11 diagrammatically illustrate the cycles of movement of the particles of the material. A particle, starting from the initial position *a* in the retort (Fig. 10) is carried upwardly by the rotation of the retort to the position *b* beyond the angle of repose, from thence it rolls by gravity at an inclination downwardly to the position *c* in initial contact with the heat transmitting plate. As the retort continues its rotation through an angle of f° , the particle of the material which has attained the position *c* in initial contact with the heat transmitting plate, will be carried downwardly by the turning movement of the body of the material to the position *d*. As the material partakes of the nature of a turning movement as a body, the position of a particle at *d*, indicates an unstable overhanging wall in the body of the material, leaving a space *e* (exaggerated in the diagram) between the body of the material and the heat transmitting plate. Because of the force of gravity, the material, however, immediately breaks as a body and the particles thereof drop down into the space referred to, thereby tending to keep that space filled at all times and providing a continual downward movement of the particles past the heat transmitting plate.

The particles of the material thus dropping downwardly and sweeping past the heat transmitting plate reach positions below that plate, from which positions they are moved upwardly (to the left as viewed in Fig. 10) again to positions beyond the angle of repose of the material, and from which latter positions the downwardly rolling movement to initial contact with the heat transmitting plate, and the movement transversally of that plate are repeated.

Fig. 11 diagrammatically illustrates the progression of these cycles of movement from the receiving to the discharge end of the retort and hence through the zones of gradually increasing temperatures.

The inclined bottom of the retort is indicated in Fig. 11 by the line *A*. A particle of the material, starting at a point *a* at the bottom of the retort is carried around by the movement of rotation of the retort in an arc, represented in projection by the line *ab*, perpendicular to the axis of rotation of the retort, until it reaches the point *b*, which is beyond the angle of repose of the body of the material. From this point the particle rolls downwardly by gravity perpendicular-

ly to the horizontal to the point *c* of initial contact with the heat-transmitting plate where it again drops perpendicularly to the point *a'*, in advance of the initial starting point *a*. This cycle of movement is repeated as indicated diagrammatically in Fig. 11, the particle attaining successively advanced positions throughout the heating zone as indicated in the diagram.

During these cycles of movement of the material undergoing treatment steam or other fluid medium is directed by means of the spaced nozzles 62 through the body of the material as well as across the surface of the heat transmitting plate. The current of the fluid medium sweeping across the heat transmitting plate modifies the heat in the heating zone and prevents that excessive temperature of portions immediately adjacent the plate which might otherwise cause cracking of the vapors. The current sweeping through the body of the material evenly distributes the heat from the particles returning from the heating zone throughout the body of the material and hence prevents the building up of regions of heat causing deleterious effects upon the vapors of distillation. The fluid medium in sweeping through the body of the material also conserves the heat within the apparatus and prevents dissipation thereof to and through the walls of the retort. And finally, the current of the fluid medium sweeping across the heat transmitting plate and through the body of the material conveys the products of distillation toward the vapor conduit. The last mentioned effect of the current of the fluid medium is of particular importance in the cycles of the distillation process.

To more clearly explain the principles of operation of these cycles of the distillation process, we may consider coal as a typical example of a material to be treated, and the lump of coal as composed of layers of bituminiferous material. In the first passage of the material in the cycle referred to, when the lump of coal comes into sufficient heat receiving relation with the transmitting plate to start the distillation of the volatile hydrocarbon contents from the outermost layer of the bituminiferous material, that outermost layer is destructively distilled and the oily distillate is separated from the other portions of that layer and exposed upon the surface of the lump. The lump continues downwardly past the heat transmitting plate to lower positions in the retort where it encounters the stream of the fluid medium. This stream forced past the lump evaporates or forcibly carries from its surface the products of distillation appearing thereon and transports them upwardly through the body of the material and to the vapor eduction conduit. The oily portions removed from the lump leaves the outer

layer in a comparatively dry and porous condition and when this lump, in repeating the cycle of movement referred to, again comes into contact or into sufficient heat-receiving relation with the heat-transmitting plate to again initiate the distillation process, it undergoes the same distillation step at a slightly higher temperature, that higher temperature being effective in evolving from the next innermost layer of the material its volatile hydrocarbon content. The hard, dry and porous outer layer is not affected as in its first passage through the cycle, but the next underlying layer is affected by the increased heat as was the outer layer in the first cycle of movement, the oily portions are distilled therefrom and exude through the porous outer layer to the surface of the lump. The lump continues its downward movement in the cycle and the current of the fluid medium removes the oily material from the surface as before. The lump continues on its movement to further repetitions of the cycle, in each of which repetitions an additional interior layer of the lump is affected in the manner stated, until substantially all of the oily or bituminous ingredients of the lump have been distilled, leaving a porous mass as coke.

While the particular advantages of the cycles of movement referred to have been emphasized in regard to the distillation of coal, they would apply also to other bituminous or resinous materials in varying degrees.

As heretofore stated, my novel process also contemplates the treatment of heavier oils, either as cuts or fractions from the distillation process above described, or obtained elsewhere, to obtain lighter oils therefrom, such as the motor fuel oils.

These heavier oils are introduced into the hotter regions of the retort, as diagrammatically indicated by the location of the discharge ends of the oil lines in Fig. 9.

It is to be observed that by the time the coal undergoing treatment in the retort reaches the zone of the introduction of the oils referred to, a substantial part, if not all, of its volatile hydrocarbon content has been distilled and removed, so that the residue is in an extremely porous condition.

This coal in its porous condition presents a particularly advantageous medium for the cracking of the oils introduced into the retort. The oil cracking becomes in effect a process of cracking upon the surface of a porous material, which is a particularly effective process of cracking. Viewing the process from the standpoint of the production of coke, also, the oil introduced greatly improves the quality of the coke. In other words, the coke resulting solely from the distillation process of the coal, is supplemented by the residue resulting from the cracking

process of the oil. A special feature (and one particularly contemplated by my invention) of the cracking of heavy oils or tars, when treating coal and such oils or tars in the apparatus, is the deposit of carbon from the oils or tars in the pores of the coke left from the coal distillation, thereby making a more dense coke. The resulting product is particularly desirable for the production of a briquetted fuel, as the more dense the coke, the less binder required to briquette the material. It is to be understood, however, that the decomposition of the heavier oils or tars may be produced in association with the distillation process of other materials than coal, although as already stated, the coke resulting as a residue from the distillation of coal presents a particularly advantageous surface for the cracking of the oils or tars in contact therewith. Any material, however, that leaves a residue from the distillation process of sufficient body may be used in association with the distillation of the heavier oils or tars.

As hereinbefore stated, the novel apparatus may be employed for other purposes than the carrying out of the novel process, and the operation of the apparatus may be varied according to the uses to which it is put. As one example, where the apparatus is used for drying or calcining materials, a fluid medium such as air or other suitable gas having a drying effect may be blown through the body of the material undergoing treatment, the pipe 61, for such use being connected with the source of the gas to be used and communication with the steam supply cut off.

What I claim is:

1. The process of distillation comprising establishing and maintaining a condition of heat of the required temperature in a heat-transmitting element having a surface adapted to engage a body composed of particles of the material to be treated with an outer layer of particles thereof in contact with said surface, maintaining the material to be treated in a unitary body in said engagement and imparting turning movements to said material as said unitary body against said surface as an abutment to bring particles from varying positions therein into contact with said surface at recurring intervals, and forcing a current of a fluid medium through said body of the material.

2. The process of distillation of carbonaceous materials comprising establishing and maintaining a localized heat distillation zone by a heated metallic element presenting an extended surface for contact therewith of the material to be distilled, maintaining a unitary body of particles of the material in contact with said surface, imparting continuous turning movements to said material as a body against said surface in a direction

to advance particles thereof across said surface, and directing currents of a fluid medium under pressure through said material.

3. The process of distillation of carbonaceous materials comprising establishing and maintaining a localized heat distillation zone by a heated metallic element presenting an extended surface for contact therewith of the material to be distilled, maintaining a collected body of particles of the material in contact with said surface and extending from said surface beyond the heat distillation zone, imparting continuous turning movements to said collected body of material against said surface in directions to advance particles of said body into and entirely through said heat distillation zone across said surface to positions beyond said heat distillation zone in recurring cycles of movements, and directing currents of a fluid medium under pressure through said body to dissipate the heat throughout said body and to blow vapors and gases of distillation therefrom.
4. The process of distillation of carbonaceous materials comprising establishing and maintaining within a suitable retort an interior localized heat distillation zone by a heat transmitting element within said retort having a surface adapted to engage a unitary body composed of particles of the material to be treated with a layer of particles thereof in contact with said surface, maintaining within said retort the material to be treated in a unitary body in said engagement and imparting turning movements to said material as said unitary body to bring particles from varying positions therein into contact with said surface at recurring intervals, and forcing a current of a fluid medium through the said body of materials.
5. The process of distillation of carbonaceous materials comprising establishing and maintaining within a suitable retort a localized heat distillation zone by a heated metallic element within the retort with said element presenting an extended surface for contact therewith of the material to be distilled, maintaining within said retort a unitary body of particles of the material in contact with said surface, imparting continuous turning movements to said material as said unitary body against said surface in a direction to advance particles thereof across said surface, and directing currents of a fluid medium under pressure through said material and inwardly from the walls of the retort.
6. An apparatus for the distillation of carbonaceous materials comprising, in combination, a tubular retort for the material to be treated, a stationary heat transmitting element positioned within said retort, spaced from the walls thereof and having a substantially flat face exposed for contact therewith of the material within said retort,
- means for feeding material into said retort, means associated with said retort for imparting movements to said material sweeping particles thereof across said face of said heat transmitting element, and a conduit positioned to withdraw gases and vapors of distillation from said retort.
7. An apparatus for the distillation of carbonaceous materials comprising, in combination, a tubular retort for the material to be treated, a stationary heat transmitting element positioned within said retort and having a substantially flat face extending longitudinally of said retort, means for feeding material into said retort, means associated with said retort for imparting continuous turning movements to the material therein in directions advancing particles of said material into and out of heat-conducting relation with said element in recurring cycles, and a conduit positioned to draw gases and vapors of distillate from said retort.
8. In an apparatus of the class described, a retort for the material to be treated rotating upon a longitudinal axis nearer the horizontal than the vertical, a stationary elongated heating element in said retort having a surface disposed in a vertical plane parallel with the axis of rotation of said retort and adjacent the axial center thereof, means for supplying material to said retort and a vapor-eduction conduit leading therefrom.
9. In an apparatus of the class described, in combination with a retort for the material to be treated, a stationary heat conducting element positioned in said retort and having an extended surface in a plane intersecting the side walls of the retort, means for maintaining said element in a condition of heat of gradually increasing degrees in one direction along said surface, means associated with said retort for moving particles of said material in recurring cycles of movement into and out of heat-conducting relation with said surface progressively in the direction of its increasing degrees of heat, and a conduit positioned to draw the vapors out of said retort.
10. In an apparatus for the distillation of carbonaceous materials, in combination with a rotatably mounted retort for the material to be treated, a stationary heating conduit extending in said retort and having a flat heat-transmitting wall, means for rotating said retort about said heating conduit and a conduit positioned to draw the vapors and gases of distillation out of said retort.
11. In an apparatus for the distillation of carbonaceous materials, in combination with a rotating retort for the material to be treated, disposed with its longitudinal axis nearer the horizontal than the vertical, a stationary heating conduit extending through said retort longitudinally thereof and having a

substantially flat and vertical heat-transmitting wall, and a conduit positioned to draw the vapors and gases of distillation out of said retort.

- 5 12. In an apparatus of the class described, in combination with a retort for the material to be treated, a heat conducting element positioned in said retort and having a substantially flat surface for contact of said material therewith over an extended area, said retort and said heat conducting element being mounted for relative rotational movement, and said heat conducting element being so positioned relative to the walls of 10 said retort as to cause said relative rotational movement to pile up the material in said retort in masses between the walls of said retort and said surface and gravity movements of particles of said masses across 15 said surface, and a conduit positioned to withdraw vapors and gases from said retort.

13. In an apparatus of the class described, in combination with a retort for the material to be treated rotating upon an axis nearer the horizontal than the vertical, an immovable heat conducting element extending into said retort and having an exposed surface in said retort extending in a plane intersecting the walls of said retort and so 20 positioned relative to the axis of rotation of said retort as to cause during said rotation the piling up of the material in said retort in masses between the walls of said retort and said heat conducting element and gravity 25 movements of particles of said masses across the surface of said heating element, and a conduit positioned to withdraw vapors from said retort.

14. In an apparatus of the class described, an elongated tubular retort mounted for rotation upon its longitudinal axis and with said axis inclined from the material inlet to the discharge end thereof, an immovably mounted heat-conducting plate extending 40 into said retort parallel with said axis of rotation, means for maintaining said plate in conditions of heat increasing from the inlet to the discharge end of said retort, ribs upon said plate disposed at an inclination 45 to the axis of rotation of said retort toward the discharge end of said retort, means for rotating said retort, and a conduit positioned to withdraw vapors from said retort.

15. In an apparatus of the class described, 50 a retort for heating materials to evolve vapors therefrom, means for feeding the material to be treated into said retort, means for heating said retort, a vapor eduction conduit extending in said retort and having inlets disposed to receive vapors or gases evolving from the material undergoing treatment and a discharge outlet outside said retort, and a sealing device disposed in said retort to prevent the movements of

said vapors or gases to portions of said 65 retort remote from said inlets.

16. In an apparatus of the class described, a retort for heating materials to evolve vapors therefrom, means for feeding the material to be treated into said retort, means for heating said retort, a vapor-eduction conduit extending in said retort and having inlets disposed to receive vapors or gases evolving from the materials undergoing treatment and a discharge outlet outside 70 said retort, and a sealing plate between said conduit and an interior wall of said retort adapted to prevent movements of said vapors or gases to portions of said retort remote from said inlets.

75 17. In an apparatus of the class described, a rotating retort for the material to be distilled, means for feeding the material into and through said retort, a vapor-eduction conduit immovably mounted independent of said retort, extending through said retort and leading therefrom, means for heating said retort, vapor inlets in the wall of said conduit within said retort, and a sealing plate pivotally mounted on said conduit adjacent said inlets and slidably engaging the interior wall of said retort.

80 18. In an apparatus of the class described, a retort for heating materials to evolve vapors therefrom, means for feeding the material to be treated into said retort, a vapor eduction conduit disposed to receive vapors evolved from said material and to discharge them from said retort, a pipe for the supply of a fluid medium under 85 pressure disposed to discharge into said retort, and a deflector disposed adjacent the discharge outlet of said pipe in position to deflect currents of said fluid medium toward said material.

100 19. In an apparatus of the class described, a retort for heating materials to evolve vapors therefrom, means for disposing the material to be treated in a body in said retort, a vapor eduction conduit disposed in said retort at one side of said body of material and adapted to receive vapors evolved from said body of material and to discharge them from said retort, a pipe for the supply of a fluid medium under pressure disposed in said retort and with nozzles disposed to direct currents of the fluid medium through said material and toward 105 said eduction conduit and a deflecting shield disposed adjacent said fluid supply pipe in position to prevent flow of said fluid medium in directions other than through the body of said material and toward said eduction conduit.

110 120 125 20. In an apparatus of the class described, a retort for heating materials to evolve vapors therefrom, means for disposing the material to be treated in a body

in said retort, a vapor eduction conduit disposed in said retort at one side of said body of material and adapted to receive vapors evolved from said body of material and to 5 discharge them from said retort, a pipe for the supply of a fluid medium under pressure disposed in said retort and with nozzles disposed to direct currents of the fluid medium through said material and toward 10 said eduction conduit and a sealing device disposed adjacent said fluid supply pipe in position to prevent flow of said fluid medium in directions other than through the body of said material and toward said eduction 15 conduit.

21. In an apparatus of the class described, a retort rotating upon its longitudinal axis and with said axis disposed nearer the horizontal than the vertical, a heating conduit 20 fixedly mounted independently of said retort, extending therethrough from the discharge end to a position closely adjacent but short of the receiving end of said retort, entirely to one side of the axial center of said 25 retort and with a heat-transmitting wall thereof disposed in a vertical plane adjacent said axial center, means for feeding

material to be treated into said retort in a body between said heat-transmitting wall and the opposite interior wall of said retort, a vapor eduction conduit disposed to one side of said body of material in said retort and adapted to receive vapors evolving from said material and to discharge the same outside said retort, a pipe for the supply of a fluid under pressure disposed adjacent a wall of said heating-conduit and having nozzles directed toward said body of material, a drag-plate extending longitudinally of said heating conduit pivotally 40 mounted on said heating conduit adjacent said nozzles and at the side thereof away from said body of material and slidingly engaging the interior wall of said retort, an end plate fixedly attached to the end of said 45 drag-plate and extending into the body of said material adjacent the receiving end of said retort and a cooperating end plate fixedly attached to the end of said heating conduit closely adjacent said first mentioned end plate.

In testimony whereof I hereunto affix my signature.

JAY J. JAKOWSKY.
